Primary Examiner — Kendra Leslie Hamilton

(57) **CLAIM**

The ornamental design for a dog harness, as shown and described.

DESCRIPTION

FIG. 1 is a perspective view of a dog harness design showing my new design.

FIG. 2 is a front view of a dog harness.

FIG. 3 is a rear view of a dog harness.

FIG. 4 is a left side view of a dog harness.

FIG. 5 is a right side view of a dog harness.

FIG. 6 is a top view of a dog harness; and,

FIG. 7 is a bottom view of a dog harness.

The broken line showing on the pet harness depicts stitching and forms part of the claimed design.
